UNITED STATES PATENT OFFICE.

WILLIAM M. DURHAM, OF PORTLAND, OREGON.

TRUSS.

1,412,391.

Specification of Letters Patent. Patented Apr. 11, 1922.

Application filed May 5, 1920. Serial No. 379,025.

To all whom it may concern:

Be it known that I, WILLIAM M. DURHAM, a citizen of the United States, residing at Portland, in the county of Multnomah, and 5 State of Oregon, have invented certain new and useful Improvements in Trusses, of which the following is a specification.

This invention has reference to a truss device for caring for and treating abdominal 10 ruptures. Trusses known to the medical profession and to the market prevent hernia at the expense of healing in that the close association with the inner wound de-vitalizes the tissues by cutting off blood sup- 15 ply to the injured containing wall and it is therefor a two fold object of the present invention to provide a truss which will not only prevent hernia but which will tend to effect a cure. The truss commonly used ef- 20 fects the former purpose but fails to provide means and results for the latter.

Broadly, the device consists of a truss adjustable about the body with a belt and provided with coiled springs with an ad- 25 justing bolt or screw between and within the coils.

With the above and other objects in view, the invention may be said generally to re-side in the details of construction, combina- 30 tion and arrangement of parts as will be hereinafter more fully pointed out, refer- 35 ence being had to the accompanying drawings, wherein—

Figure 1 is a plan view of the device.

Figure 2 is a vertical cross section taken on line 2—2 of Figure 1.

Figure 3 is a fragmentary view disclosing the spring coil and Figure 4 a detailed sec-tional view of the adjusting member.

40 The fault as found in the usual truss and which this device seeks to correct is that the commonly used truss, now in vogue, is con- 45 vexed at the point of pressure. This pro- posed truss is concaved, and therefore re- versed in application to the wound. The truss is supported about the body by means of a curved rod 1 which is bent to fit snugly about the hips, being provided with soft pads 2, each of which carry a belt section 3 50 by which the device may be adjusted about the body. Clamping the rod on one side of the bulge 4 are a pair of clamp plates 5 and 6 which are held together by long shank screws 7 so as to enable the plates to be ad- 55 justed along the rod to any desired location whenever desired, by loosening the screws sufficient to enable the plates to be moved. Associated with the clamp plates is a stud 8 which passes transversely through a smooth bored opening formed centrally in 60 each plate the stud being cylindrical so as to revolve easily within the opening and provided at its inner end with a threaded cavity or socket hole 9. At its outer end the stud is provided with a finger grip 10 65 to facilitate the turning of the stud, this finger grip consisting either of a wire in- 70 serted through an opening at the end of the stud and bent into the shape illustrated or it may be formed in any other manner con- 75 venient and suitable for the purpose in view. To the inner socket end of the stud is se- 80 cured a pad member comprising an enlarged solid head 10 which is adapted to bear di- rectly upon the hernia being provided with the usual convexed surface common to pads of this character. This pad is provided with a threaded stem 11 which is adapted to be received in the socket 9 of the stud as shown to advantage in Figure 4 of the drawing. 85 Arranged between the pad and the outer- 90 most clamp plate 5 is an elastic member formed of a single wire having one end embracing the stud 8 between the clamps and coiled upwardly in outwardly receding con- 95 volutions to provide a coil 13 connected to a similarly formed coil 14 at the other ter- 100 minal of the wire by the linking convolu- 105 tion 15. The elastic member is thus seen to comprise two resiliently spaced coils one of 110 which is anchored to the clamping plates 5 and 6 while the other bears outwardly against the head 10, its terminal end 17 be- 115 ing coiled about the stud 8 rearwardly of the pad as shown to advantage in Fig. 4. 115 The head 10 and the shank 8 together form the adjusting bolt or screw of the device and as shown extend centrally between and within the convolutions of the two spring coils so that whenever the inner coil 15 100 which is adapted to exert pressure out- 105 wardly of the hernia or rupture is desired to be adjusted so that it will present a more or less convexed face, the stud 8 is merely rotated in its bearing causing the threaded 110 stem 11 of the pad to move inwardly of the socket, drawing the pad 10 inwardly and contracting the center coil 16 of the spring 15, thus fixing the extent of concavity of the truss at the point of application.

In operation, the truss is positioned upon the person in the usual manner so that the pad 10 bears directly upon the hernia while the outermost coil of the inner spring 15 presses against the abdomen at a distance outwardly of the edges of the rupture so as to allow the blood to circulate to the opening to feed and nurture the injured portion of the abdominal walls, thus facilitating its 10 healing, while at the same time operating to prevent protrusion at the point of rupture. The elasticity of the wire coils enables the wearer freedom of movement and tends by absorbing such pressure and distributing it 15 uniformly around and about the rupture to prevent any such movement resulting in increased pressure at one part. Whereas trusses have formerly resulted in a prevention at the expense of healing it is thought 20 that with the improvement embodied in the invention above described the wound can be treated in such a manner as to facilitate its healing, while at the same time rendering the truss more comfortable to the wearer.

25 Having thus described the invention what

I claim as new and desire to secure by Letters Patent is:—

A hernia truss consisting of a curved rod, a pair of plates clamped to said rod, screws to hold said plates in adjusted position on 30 said rod, a cylindrical stud having a threaded bore at one end passing transversely through suitable openings in said plates, means for rotating said stud, a pad member comprising an enlarged head having a threaded stem held in said threaded bore, an elastic coil member formed of a single length of spring wire with one end clamped between said pad plates, and said stud, the other end being clamped between 35 said clamp plates, whereby said pad is arranged to be held in a central position with respect to said coil spring, as in the manner set forth.

In testimony whereof I affix my signature 45 in presence of two witnesses.

WILLIAM M. DURHAM.
